UNITED STATES PATENT OFFICE.

ALVIN LEROY FISHER, OF ALMENA, KANSAS.

ANIMAL-YOKE.

SPECIFICATION forming part of Letters Patent No. 591,337, dated October 5, 1897.

Application filed April 24, 1896. Serial No. 588,943. (No model.)

To all whom it may concern:

Be it known that I, ALVIN LEROY FISHER, a citizen of the United States, residing at Almena, in the county of Norton and State of Kansas, have invented a new and useful Animal-Yoke, of which the following is a specification.

My invention relates to animal-yokes, and has for its object to provide a simple and efficient device having means for adjustment to suit the size of the animal to which it is to be applied and being reversible to suit different kinds of animals, as cattle, horses, &c.

Further objects and advantages of this invention will appear in the following description, and the novel features thereof will be particularly pointed out in the appended claim.

In the drawings, Figure 1 is a perspective view of a yoke constructed in accordance with my invention applied to a head of cattle. Fig. 2 is a similar view showing the yoke in the inverted position in which it may be arranged when applied to horses. Fig. 3 is a detail view of the nose-ring. Fig. 4 is a similar view of the snap-hook for attaching the chain, strap, or rope to the frame of the yoke. Fig. 5 is a detail view of a portion of the cross-bar partly broken away to show the construction of clamping-bolt employed for securing the arms of the yoke-frame thereto.

Similar numerals of reference indicate corresponding parts in all the figures of the drawings.

1 designates a cross-bar which connects the side arms 2 and 3 of a looped yoke-frame, said frame being preferably constructed of heavy wire or metal rod of even thickness throughout, bent upon itself at its center. The extremity of the arm 2 is bent forwardly to form a hook 4, and the extremity of the arm 3 is similarly bent to form a hook 5, an eye 6 being also formed in the long arm below its terminal hook and above the plane of the cross-bar.

The looped yoke-frame is adapted to extend around the neck of the animal, and in order to adapt the length thereof from the cross-bar to its looped end to the size of the neck upon which it is fitted I form an adjustable connection between the cross-bar and the arms 2 and 3. In the construction illustrated

this connection is formed by means of clamping-bolts 7, provided at one end with hooks to engage the arms and having shanks extending through horizontal openings 8 in the cross-bar and engaged at their extremities by nuts 9. By tightening the nuts the hooks are drawn toward the contiguous edge of the cross-bar, thus clamping the arms frictionally. In order to provide for lateral adjustment of the arms to suit the width or thickness of the neck, a plurality of openings 8 are provided.

The nose-ring which I prefer to employ in connection with my improved yoke consists of a forked member 10, having terminal eyes 12, and a needle 13, adapted to pass through the cartilage of the nose of the animal and engage said eyes at opposite sides thereof. This needle is provided at one end with a ring 14 and is adapted to be bent at the other end to form a hook 15 after insertion to prevent displacement.

Connected to the loop of the forked member is one extremity of a chain, strap, or rope 16, the other end of this flexible member being provided with a snap-hook 17 for engagement with the loop or eye 6 on the arm 3. This snap-hook preferably consists of a single blank of spring-wire bent upon itself at an intermediate point to form approximately parallel sides 18 and 19, the side 18 terminating in a seat 20 for engagement with the free end of the side 19.

The contact of the horns formed by the portions of the arms 2 and 3 above the plane of the cross-bar with an obstruction, such as a part of a fence, will cause backward strain upon the flexible connection and hence upon the nose-ring, and will thus induce the animal to retreat, and it will be understood that while the nose-ring above described is preferable the device may be used in connection with a ring of the ordinary construction, or with the nose piece or ring 10^a of an ordinary halter, as illustrated in Fig. 2 of the drawings.

In addition to the above-described means for preventing cattle from breaking over or through fences I employ a pendent or swing-arm 21, terminating at its upper end in a ring 22, which is fitted upon the looped portion of the yoke-frame and is adapted to be applied and removed at the extremity of the

short arm 2. This pendent arm terminates at its lower end in a forwardly-extending hook 23, and is provided at an intermediate point with an integral eye 24. This arm is 5 adapted to engage with wires or other parts of a fence over which the animal attempts to pass, and the intermediate eye is provided to facilitate connection by means of a chain, strap, or rope (not shown) with a halter in 10 case it is preferable to arrange the device in this way rather than employ a nose-ring. This alternative manner of arranging the yoke is especially adapted for use in connection with horses, mules, and the like; but 15 another arrangement is shown in Fig. 2, in which the yoke is inverted to bring the loop at the top of the neck. In this case the swinging arm is dispensed with and connection is made between the halter and the eye 6 on the 20 extension of the arm 3 of the yoke-frame by means of a chain, strap, or rope 25.

From the above description it will be seen that the device is readily adjustable to all sizes of animals and is adapted to cause rearward strain upon the nose thereof when the yoke meets with an obstruction, thus serving to deter without injuring or causing unnecessary pain.

Various changes in the form, proportion, 30 and the minor details of construction may be

resorted to without departing from the spirit or sacrificing any of the advantages of this invention.

Having described my invention, what I claim is— 35

In a reversible animal-yoke, the combination with a suitable nose-piece, of a yoke formed of a single yielding rod or wire bent intermediate its ends to produce a pair of side arms terminating in hooks, one of the 40 yoke side arms being coiled at an intermediate point to form an eye 6, a cross-bar 1 intersecting said side arms, clamping-bolts adjustably fitted in the bar and formed at one 45 end with hooks having a clamping engagement with said side arms, a spring-wire snap-hook 17 having its closed end portion loosely hung in the eye 6 of one of the yoke side arms, and a flexible connection engaged at one end with said nose-piece and having its other 50 end detachably engaging with said spring-wire snap-hook 17, substantially as set forth.

In testimony that I claim the foregoing as my own I have hereto affixed my signature in the presence of two witnesses.

ALVIN LEROY FISHER.
